UNITED STATES PATENT OFFICE.

JAMES H. CURRY, OF WILKINSBURG, PENNSYLVANIA.

BEAN-SHOOTER.

No. 822,190.

Specification of Letters Patent.

Patented May 29, 1906.

Application filed August 7, 1905. Serial No. 272,999.

To all whom it may concern:

Be it known that I, JAMES H. CURRY, a citizen of the United States, residing at Wilkinsburg, in the county of Allegheny and State of Pennsylvania, have invented certain new and useful Improvements in Bean-Shooters, of which the following is a specification, reference being had therein to the accompanying drawings.

- 10 The primary object of this invention is to provide for compactly folding the fork-arms of a bean-shooter upon the handle thereof, so that the device may be conveniently carried in the pocket or packed in a small space.
- 15 A further object is to so construct the handle to which the fork-arms are pivoted that it operates to securely hold the arms either in outturned or in folded position.

In the accompanying drawings, Figure 1 is a perspective view of the improved device. Fig. 2 is a side view of the fork when folded, part of one side of the handle being broken away. Fig. 3 is an edge view with a portion thereof sectioned on line 3 3 of Fig. 2. Fig. 4 is a top plan view of the handle with the arms folded, and Fig. 5 is a similar view of the same with the arms turned outward.

The handle is recessed longitudinally, forming the two side members A, which are connected at their lower end at B. In the preferred adaptation the handle is formed of a single piece of wood having a saw-kerf which extends nearly to its lower end, thereby providing the necessary space between the handle members, the wood possessing sufficient flexibility or spring to secure the fork-arms either in outturned or folded position.

Pivoted between and near the upper ends of the handle members on rivets C are the opposite fork-arms D, which are preferably, though not necessarily, formed of round wire. Their pivoted ends D' are flattened or tapered, so that members A may be drawn quite close together by rivets C, and thus between them provide the necessary arm-holding tension. Above rivets C the adjacent faces of members A are slightly recessed, as indicated at A', to form clamping or holding sockets for arms D when turned outward, the round section of the arms fitting therebetween at such time, as indicated at Fig. 5, and the flattened or tapered portions D' operating as wedges to so separate members A when the arms are turned upward as to admit the round section thereof into the holding-

sockets. When the arms are folded upon the handle, as indicated in Fig. 3, members A are again under slight tension at about a line E E, Fig. 3, the pressure being sufficient to retain the forks with their extremities 60 turned inward between handle members A, as shown.

While the sling F of Fig. 1 is not illustrated in the other views, it will be readily understood that it in no way interferes with the 65 folding and unfolding of the fork-arms. With a fork of the character described the bean-shooter may be very compactly folded and conveniently carried in the pocket or placed in a small space.

I claim—

1. A fork for a bean-shooter comprising a handle, and fork-arms separately pivoted to the handle and adapted to fold thereon.
2. A fork for a bean-shooter comprising a 75 handle adapted to exert arm-holding pressure, and arms separately secured to the handle and adapted to be held by the pressure thereof in adjusted position.
3. A fork for a bean-shooter comprising a 80 recessed handle, and fork-arms secured in the handle-recess and adapted to fold thereon in opposite directions.
4. A fork for a bean-shooter comprising a 85 recessed handle, and fork-arms pivoted in the handle-recess and adapted to fold thereon, the frictional pressure of the handle members operating to hold the arms either in outturned or in folded position.

5. A fork for a bean-shooter comprising a 90 recessed handle, and fork-arms pivoted in the handle-recess and having their pivoted ends reduced or tapered and closely fitting the recess and with the full section of the forks adapted to enter the handle-recess when the 95 forks are turned outward and also when folded upon the handle.

6. A fork for a bean-shooter comprising a recessed handle, and fork-arms pivoted in the handle-recess and having their pivoted ends 100 reduced and closely fitting the recess, the faces of the recess having depressions to receive the forks when the latter are turned outward.

7. A fork for a bean-shooter comprising 105 two handle members connected at their lower ends, and fork-arms pivoted between the handle members and adapted to fold backward into the space between the latter, the pivoted ends of the arms closely fitting the recess and 110

adapted to be held by the frictional pressure of the handle members either in outturned or in folded position.

8. A fork for a bean-shooter comprising a handle, and fork-arms separately pivoted to the handle and adapted respectively to fold backward on opposite sides thereof.

In testimony whereof I affix my signature in presence of two witnesses.

JAMES H. CURRY.
